201,409

AIRCRAFT

William J. Flett, 3711 Marshall Road, Drexel Hill, Pa.

Filed Sept. 1, 1964, Ser. No. 81,550

Term of patent 14 years

(Cl. D71—1)

FIG. 1 -

Des. 201,409

PAGE 2

FIG. 2 -

Des. 201,409

PAGE 3

FIG. 3 -

FIG. 4 -

FIG. 1 is a perspective view of an aircraft showing my new design and embodying a rotary wing;

FIG. 2 is a perspective view of a modified form of the aircraft of FIG. 1 embodying a jet engine;

FIG. 3 is a perspective view of the opposite side of the aircraft shown in FIG. 1;

FIG. 4 is a perspective view of the opposite side of the aircraft shown in FIG. 2.

I claim:

The ornamental design for an aircraft, substantially as shown and described.
